UNITED STATES PATENT OFFICE.

HENRY H. JACOBOWITZ, OF BROOKLYN, NEW YORK.

DESIGN FOR A SIGN-LETTER.

47,426.

Specification for Design.

Patented June 8, 1915.

Application filed February 26, 1915. Serial No. 10,870. Term of patent 14 years.

To all whom it may concern:

Be it known that I, HENRY H. JACOBOWITZ, a subject of the Russian Empire, residing at Brooklyn, in the county of Kings and State of New York, have invented a new, original, and ornamental Design for Sign-Letters, of which the following is a specification, reference being had to the accompanying drawing, forming part thereof.

Figure 1 is a front elevation of a sign letter, showing my new design, and Fig. 2 is a horizontal sectional view of a sign letter, showing my new design.

I claim:

The ornamental design for a sign letter, as shown.
